UNITED STATES PATENT OFFICE.

ERNEST WALTER HIVES, OF DERBY, ENGLAND.

DEVICE FOR PRIMING THE INDUCTION-PIPES OF INTERNAL-COMBUSTION ENGINES.

1,206,221.

Specification of Letters Patent. Patented Nov. 28, 1916.

Application filed February 16, 1916. Serial No. 78,765.

To all whom it may concern:

Be it known that I, ERNEST WALTER HIVES, a subject of the King of Great Britain and Ireland, residing at Nightingale 5 Road, Osmaston Road, Derby, in the county of Derby, England, have invented a new and useful Device for Priming the Induction-Pipes of Internal-Combustion Engines, of which the following is a full and complete 10 specification.

This invention relates to devices for priming the induction pipes of internal combustion engines for the purpose of facilitating starting, and it has for its objects to reduce 15 the number of revolutions that the crank-shaft of the engine usually has to be turned before the engine begins to function in its normal manner, to overcome the defects in existing devices, and to provide a more simple 20 and conveniently handled arrangement than has hitherto been employed.

I attain the objects of this invention by employing in conjunction with the float chamber of the carbureter a supplemental 25 chamber—of predetermined size—which is in communication with said float chamber by means of a suitable port or passage in which is a non-return valve. This supplemental chamber can be put into connection 30 with the induction pipe of the engine and is provided with means whereby air under slight pressure can be introduced for the purpose of injecting the liquid fuel in the supplemental chamber into the induction 35 pipe of the engine in the form of a spray.

It will be understood that according to the present invention an explosion mixture is introduced into the induction pipe (and the cylinder whose inlet valve is open) 40 which on being compressed and ignited will fire and therefore rotate the crankshaft of the engine. After the liquid fuel in the supplemental chamber is used up the engine should be drawing a mixture direct from the carbureter; if it does not, the induction 45 can be primed again.

In the accompanying drawing which illustrates—by way of example—some forms this invention may assume, Figure 1 is a 50 diagrammatic view in elevation showing the general arrangement, and Fig. 2 is a view in sectional elevation—on an enlarged scale—showing one form of construction.

Throughout the views similar parts are 55 marked with like letters of reference.

Referring to Fig. 1 of the accompanying

drawing, *a* designates the cylinders of the engine, *b* the carbureter, *b*¹ the float chamber of the carbureter, and *c* the induction pipe connecting the carbureter to the engine. 60

Referring to Fig. 2 of the accompanying drawing. Below the float chamber *b*¹ of the carbureter is a supplemental chamber *d* which is in communication with said float 65 chamber by means of a non-return valve *e*. To this chamber *d* are connected two pipes *f* and *f*¹ each of which extends vertically at least as high as the normal level of the liquid fuel in the float chamber so that said 70 pipes form in effect part of the chamber *d*.

A hand pump *m* is connected to the pipe *f* for introducing air into the supplemental chamber *d*. This hand pump may conveniently be the one employed to introduce air 75 into the fuel supply tank when pressure feed is employed, in which case the pipe *f*, the pump *m*, and a pipe *n* leading to the fuel supply tank are all connected to a three-way tap *h*, so that by suitably operating the tap *h* the hand pump *m* can be put 80 into communication either with the pipe or passage *f* or with the pipe *n*. The end of the pipe or passage *f*¹ terminating in the induction pipe *c* is so shaped as to form 85 a spraying nozzle.

In the extension of the pipe or passage *f*¹ is a tap *o* which is inter-connected with the tap *h* by means of arms *h*¹ and *o*¹ and a coupling rod *r*. As it is undesirable for the tap *o* to remain open when the engine is running, owing to the fact that if such were the case fuel would be sucked through the pipe or passage *f*¹ from the float chamber, means such as the spring *s* is provided to 90 automatically close the tap *o* when the operation of priming is complete. 95

To prime the induction pipe of the engine the taps *h* and *o* are manipulated to put the pipe *f* into communication with the hand pump *m* and the pipe *f*¹ into communication with the induction pipe *c* of the engine. The hand pump is then operated so as to force air into the pipe or passage *f* which displaces the liquid fuel therein and injects it into the induction pipe in the form of a spray, which will vary in density according to the area of nozzle employed. A predetermined number of strokes of the hand pump will provide a suitable explosive mixture in the induction pipe which, on being sucked into the cylinders and afterward 100 105 110

compressed when cranking the engine, will fire in the usual way.

The function of the non-return valve *e*, which may be of the reed type as shown, 5 or of any other suitable type, is to permit the liquid fuel to flow from the float chamber into the supplemental chamber *d* and pipes or passages *f* and *f'* in which it will attain the same or approximately the same 10 level as in the float chamber as shown by the dot and dash line *xx* in Fig. 2, and to prevent any pressure in said pipes or passages and in the supplemental chamber *d* passing into the float chamber and thus 15 avoid any disturbance of the level of the liquid at the jet or jets of the carbureter when the hand pump *m* is being operated, but in some cases, for instance if the carbureter is an inefficient one for starting 20 without flooding it, the non-return valve may be dispensed with.

What I claim as my invention, and desire to secure by Letters Patent is:—

1. A priming device for internal combustion engines comprising in combination with the float chamber of the carbureter and the induction pipe connecting the carbureter to the engine, of a supplementary chamber, a 25 port or passage connecting said chamber to the float chamber of the carbureter, a pipe or passage connecting the supplemental chamber to the induction pipe of the engine, said pipe having a vertically arranged part extending as high as the normal level 30 of the liquid fuel in the float chamber, a spraying nozzle on the end of said pipe within the induction pipe, a hand-operated air pump, a pipe or passage connecting the supplementary chamber of the carbureter 35 with the air pump, a tap for shutting off the connection between the supplementary chamber and the induction pipe, means for shutting off the connection between the supplementary chamber and the air pump, and 40 means for causing the tap in the pipe connecting the supplementary chamber with the induction pipe to close automatically.

2. In an internal combustion engine, the 45 combination with the carbureter and induction pipe, of a supplemental chamber in connection with the float chamber of the carbureter by means of a suitable port or passage; a non-return valve in said port or

passage, a pipe or passage connecting said supplemental chamber with the induction 55 pipe of the engine and terminating therein in a spraying nozzle, a tap or valve in said pipe or passage, a pipe or passage connecting the supplemental chamber to the fuel supply tank, a three-way tap in said pipe 60 or passage, and a hand operated air pump connected to said three-way tap.

3. In an internal combustion engine, the combination with the carbureter and induction pipe, of a supplemental chamber in 65 connection with the float chamber of the carbureter by means of a suitable port or passage, a non-return valve in said port or passage, a pipe or passage connecting said supplemental chamber with the induction 70 pipe of the engine and terminating therein in a spraying nozzle, a tap or valve in said pipe or passage, a pipe or passage connecting the supplemental chamber to the fuel supply tank, a three-way tap in said pipe 75 or passage, a hand operated air pump connected to said three-way tap, and means for automatically closing the tap or valve in the pipe or passage connecting the supplemental chamber with the induction pipe. 80

4. In an internal combustion engine, the combination with the carbureter and induction pipe, of a supplemental chamber in connection with the float chamber of the carbureter by means of a suitable port or passage, a non-return valve in said port or passage, a pipe or passage connecting said supplemental chamber with the induction pipe of the engine and terminating therein in a spraying nozzle, a tap or valve in said 85 pipe or passage, a pipe or passage connecting the supplemental chamber to the fuel supply tank, a three-way tap in said pipe or passage, a hand-operated air pump connected to said three-way tap, a coupling 90 between the three-way tap and the tap or valve in the pipe or passage connecting the supplemental chamber with the induction pipe, and means for automatically closing the tap or valve in the pipe or passage connecting the supplemental chamber with the induction pipe. 95

In testimony whereof I have signed my name.

ERNEST WALTER HIVES.
